UNITED STATES PATENT OFFICE.

JOHN H. NELSON, OF CHICAGO, ILLINOIS, ASSIGNEE TO HARRY A. DOUGLAS, OF BRONSON, MICHIGAN.

LOCKING MECHANISM.

Application filed November 9, 1925. Serial No. 67,857.

My invention relates to locking mechanism and is of particular service in connection with combined switches for governing the ignition or power controlling circuits and the lighting circuits of automotive vehicles and which combined switches employ switch handles for controlling the lighting circuits and locks for controlling the ignition or power controlling circuits. 5 A prior switch of this class is provided with an enclosing casing for the contacting mechanism, this casing having a central tubular portion projecting outwardly beyond the casing into the hollow hub of the lighting circuit controlling handle. This tubular casing portion that is surrounded by the hub of a handle also constitutes a hollow member of the lock. This hollow lock member encloses a tumbler barrel that carries a number 10 of tumblers movable transversely of the hollow lock member and tumbler barrel and which enter openings formed in opposite sides of the hollow lock member after the tumbler barrel is turned by the inserted key. 15 to bring the tumblers into register with said openings and in consequence of the withdrawal of the key following this turning movement of the tumbler barrel, the tumbler barrel being locked in fixed relation with the 20 hollow lock member when the tumblers enter the openings in this member. When the key is inserted to withdraw the tumblers from said openings, the tumbler barrel may be turned by the inserted key to remove the 25 tumblers from alignment with the openings to bring the tumblers out of locking relation with the hollow lock member, imperforate portions of this member then holding the tumblers out of locking relation with it. The tumbler barrel is in operating relation with the contact actuator within the casing that governs the ignition circuit. 30 When the key is inserted and turned to turn the tumbler barrel to an unlocked position, the ignition circuit is consequently closed. When the key is reversely turned, the tumbler barrel is reversely turned, and the ignition circuit is consequently opened, the tumblers then being in register with the openings 35 in the hollow lock member. When the key is withdrawn following its reversed turning movement, the tumblers are free to enter the openings in the hollow lock member to lock the ignition circuit open. 40

55 In these prior switches, the tumbler barrel

or rotatable lock member was so positioned with relation to the handle, that occasionally the handle, in being moved to adjust the lighting circuits, would turn this lock member from its ignition circuit closing position to an ignition circuit opening position, thereby bringing the engine to rest unless this faulty operation were at once observed.

It is the general object of my invention to provide an improved locking mechanism for locking the ignition switch in ignition circuit opening position. This locking mechanism is inclusive of a key operated tumbler barrel that is preferably in direct turning engagement with a contact actuator 60 pertaining to the ignition circuit and is so related to the lighting switch handle as not to be incidentally operable thereby. The tumblers are desirably disposed longitudinally of the axis of the tumbler barrel, this 65 barrel being formed to receive spring-pressed holding pins carried by the shell or hollow lock member that is preferably fixed upon the outer casing end wall and extends within the casing. These pins are in their holding positions when the ignition circuit is to be locked open. By means of this construction, I am enabled to reduce the aggregate depth of the switch structure. The lock 70 of my invention includes a holding part 75 upon the inner end of the lock member that is fixed upon the end wall of the casing, this holding part being within the casing and upon the inner end of this lock member that projects into the casing and there 80 is also employed a key controlled lock member between this holding part and said casing end wall. Said holding part desirably carries the spring pressed pins but this feature of the invention is not to be limited to 85 the employment of the spring pressed pins and the cooperating tumblers.

In carrying out my invention in the preferred way, I provide a handle operated, light circuit controlling, contact actuating ring within the switch casing, a second contact actuating ring surrounded by the first and in controlling relation to the ignition circuit, the hollow lock member being surrounded by the rings. This tubular or hollow lock member is desirably fixedly secured at its outer end to the outer end wall of the casing, thereby constituting an inward continuation of the casing instead of an outward continuation of the casing as hitherto. 100 105 110

This continuation enables me to employ the tumbler barrel to directly hold the ignition circuit controlling contact actuating ring to lock the ignition circuit open.

6 The invention will be more fully explained in connection with the accompanying drawings in which Fig. 1 is a front view of the preferred embodiment of the invention; Fig. 2 is a rear view; Fig. 3 is a sectional view on line 3-3 of Fig. 1, on a larger scale, with the key inserted; Fig. 4 is a sectional view on line 4-4 of Fig. 3, on a smaller scale; Fig. 5 is an enlarged front view of the locking mechanism and a broken portion of the front casing end wall; Fig. 6 is a sectional view on line 6-6 of Fig. 3 with the ignition switch contact actuating ring absent; Fig. 7 is a side view of the locking mechanism, parts of the casing and 10 the inner actuating ring being shown in section; Fig. 8 is a sectional view on line 8-8 of Fig. 3; Fig. 9 is a sectional view on line 9-9 of Fig. 4; Fig. 10 is a sectional view on line 10-10 of Fig. 9; Fig. 11 is a 15 perspective view showing two complementary parts of the lock mechanism in separated relation; Fig. 12 is a perspective view showing the hollow lock member and a portion of the casing end wall that supports it, prior 20 to the assembly of these two elements; Fig. 13 is a sectional view on line 13-13 of Fig. 3, showing the tumbler barrel in circuit opening position; Fig. 14 is a view similar to Fig. 13, but showing the tumbler barrel 25 in circuit closing position; and Fig. 15 is a diagrammatic view illustrating the relationship of the handle and lock with the switching mechanism.

40 The switching mechanism to be later described is enclosed within a casing that is preferably cylindrical. The casing is desirably formed of sheet metal and has one end wall 1 integrally formed with its cylindrical wall 2. The other end wall of the 45 casing is illustrated in the form of a contact carrying disc 3 of insulating material, this disc having bayonet pins 4 which are received in bayonet slots 5 formed in the casing wall 2. The end wall 3 thus constitutes a removable closure affording access 50 to the interior of the casing for the purpose of locating the operating parts of the switching mechanism therein and for the inspection and replacement of these parts. The 55 disc is held in assembly with the casing by spring pressure exerted rearwardly thereon and furnished by spring-pressed contacts, later to be described, that are contained in the casing. As will more fully appear, 60 some of these spring-pressed contacts are complementary to contacts 6, 6', 7, 8, 8', 9, 9', 9² and 10' carried by the closure disc 3 and other of these spring-pressed contacts are complementary to and engageable with 65 the ignition contact 10 and the battery con-

tact 11 also carried by the disc 3. The contacts 13, 14, 15 and 16, that pertain to the contacts 6, 6', 7, 8, 8', 9, 9', 9² and 10', are in the nature of bulging formations formed in a ring 17, this ring and these contacts being diagrammatically indicated in Fig. 15. The contacts 18, 19 and 20 that pertain to the contacts 10 and 11 are also in the nature of bulging formations which, in the case of these contacts, are formed in a second contact carrying ring 21 surrounded by ring 17. 70

75 The particular nature of the circuits controlled by the handle and lock is not germane to my invention and, therefore, the circuit arrangement in Fig. 15 need not be particularly described. It will suffice to say that the switching arrangement illustrated, is such that the lighting switch handle, when adjusted to parking position or an off position, establishes gaps in the ignition circuit 80 so that this circuit may not then be closed but is free to be closed when the lighting switch is adjusted to "day," "dim," or "bright" positions.

85 The metallic rings 17 and 21 are pressed toward the contact carrying disc 3 in order that the contacts on said rings may press against the complementary contacts on the carrier 3 or on the insulation between these contacts, according to the circuit adjustment desired. The desired spring pressure is exerted by preferably providing each of the contacts 13, 14, 15 and 16 on the ring 17 and the contacts 18, 19 and 20 on ring 21, with the spring devices illustrated in 90 Figs. 3 and 8. Each spring device includes a spring barrel 23 which houses a spring 24 and which presses the element (17 or 21) carrying it, toward the contact carrier 3. The springs 24, in the construction illustrated, carry no essential parts of the currents. The spring barrels 23 constitute means for flexibly coupling the contact carriers 17 and 21 with the actuators for these contact carriers. The actuator for the contact carrying ring 21 is desirably in the form of an insulating ring 26 which is coaxial with the casing. The spring barrels 23 carried by the ring 21 are slidably received within recesses 27 formed in the ring 26. 95 As the ring 26 is turned, by means which will later be described, the contacts 18, 19 and 20 on the ring 21 will ride into and out of cavities formed in the contacts 10 and 11 and also formed in the insulating contact carrying disc 3, the extent to which the ring 26 is spring-pressed away from the disc 3 being limited by its engagement with the casing end wall 1. 100

105 The contact actuator for the contact carrying ring 17 is desirably in the nature of another insulating ring 28 that is located in the zone of and which surrounds the ring 26, the ring 28 being coaxial with the casing and the rings 17, 21 and 26. The rings 17 and 28 110

are substantially of the same diameters and are coupled in a manner similar to that in which the ring 26 and ring 21 are coupled as hitherto stated. The bore of the ring 28 has radially disposed enlargements 29 which receive the prongs 30 formed upon the hub portion 31 of a handle 32 and which project through arcuate slots 33 formed through the end wall 1 and concentric therewith. A plate 34, preferably circular and slightly dished, is suitably assembled with the casing end wall 1 upon the exterior thereof, as by means of rivets 35. The plate 34 may, if desired, constitute the mounting plate for the switch structure in which event it may be formed with screw receiving holes 34'. The handle hub 31 has a circular flange portion 31' that is concentric with the casing and which directly carries the prongs 30. This circular portion 31' is in the nature of a flange off-set with respect to the body portion of the hub surrounded thereby to form an annular shoulder 36 concentric with the handle and casing and engaging the inner edge of the circular opening formed in the plate 34 concentrically with the handle and casing. The flange 31' is received in the space between the plate 34 and the casing end wall 1, the flange being in engagement with both plate and end wall at its circular edge to restrain the handle from movement along the casing axis. The shoulder 36 and the surrounding plate 34 confine the handle to turning movement upon the axis of the casing. The range of oscillation of the handle is defined by the lengths of the arcuate slots 33, this range of movement being sufficient to enable the handle to turn the contact actuator 28 in either direction and to a sufficient extent to close the selected lighting circuit or to open all lighting circuits.

The contact actuator 26 that determines the position of the ring 21 is, in the embodiment of the invention illustrated, operated by a lock tumbler barrel 37 which is confined within the hollow lock member 38 which is preferably in the nature of a tubular extension of the casing end wall 1 that projects from this casing end wall into the interior of the casing. This tumbler barrel is in line with the axis of the handle.

The hollow lock member 38 is formed with a flange in the nature of a bead 39, at its outer end, and is inturned at this end to form an annular rim 40 which overlaps the outer end of the tumbler barrel 37. The hollow lock member 38 has holding wing portions 39' which are outwardly bent to snugly fill the spaces between the arcuate projections 1' formed upon the casing end wall 1. The bead 39 and the wings 39' cooperate with the end wall which is gripped between these parts when the wings 39' are out-turned to prevent the hollow lock mem-

ber from moving longitudinally of the casing axis. The arcuate projections 1' on the casing end wall 1 serve to prevent the hollow lock member from being turned.

The rim 40 is formed with key inlets 41 at opposite sides thereof and with which the keyway 42 in the tumbler barrel is brought into communication. The tumbler barrel is turned from the ignition circuit closing position, illustrated in Fig. 14, to ignition circuit opening position, illustrated in Fig. 13. When the keyway 42 and the key inlets 41 are in register, as indicated in Fig. 13, the key 43 may be inserted or withdrawn. When the key is withdrawn the ignition circuit is locked open. When the key is inserted and turned, the ignition circuit is closed. The tumbler barrel has laterally extending wings 44 which pass through lateral openings 45 formed in the hollow lock member 38, these wings being surrounded by ring 26 and entering guideways 46 in this ring and which guideways are in the nature of enlargements of the bore of this ring. The sides of the bore enlargements 46 are engaged by the wings of the tumbler barrel and constitute holding formations which are engaged by these wings to turn the ring 26 and to hold it in its selected adjustments. The connection established between the tumbler barrel 37 and the ring 26 by means of the wings 44 is thus a sliding or splined connection that is effected in the zone of the hollow lock member 38. The tumblers 47 which are employed to hold the tumbler barrel and the contact actuating ring 26 from rotation are desirably arranged longitudinally of the axis of the tumbler barrel and are slidable within channels formed in the tumbler barrel along its axis. These tumblers serve to remove the holding pins 48 from the tumbler channels when the key is inserted, preparatory to the rotation of the tumbler barrel from the position in which it locks the ignition circuit open to the position in which it closes the ignition circuit, said holding pins being free to enter the tumbler channels when the tumbler barrel is restored to circuit opening position and the key is withdrawn, said pins then serving to lock the ignition circuit open. The locking pins 48 are arranged in channels that are formed in a pin carrier 49, constituting a holding part to hold the key operated lock member 37 from turning and which is secured to the inner end of the hollow lock member 38, the channels in the carrier 49 that contain the pins 48 constituting continuations of the channels in the tumbler barrel when this barrel is turned to circuit opening position. Springs 50 press outwardly upon the pins 48 so that when the tumbler channels in the tumbler barrel are aligned with the pin channels in the pin carrier and the key is withdrawn, the lock-

ing pins will enter the tumbler channels to a limited extent and without being ejected from the channels in the pin carrier whereafter the tumbler barrel cannot be turned.

5 The pin carrier 49 also serves to center the tumbler barrel 37, it being provided with a reduced outer end portion 51 that enters a socket 52 on the inner end of the tumbler barrel. The pin carrier and the outer end 10 of the lock member 38 cooperate to define a fixed axis of rotation for the tumbler barrel, this axis including the center of the opening 53, in the end wall 1, that receives the outer end of lock member 38 and also 15 including the center of the opening 54 in the handle hub through which the key is passed to the lock. The key or lock opening 54 in the handle, the casing opening 53 and the bore of the lock member 38 are thus 20 in register and coaxial with the tumbler barrel, the contact carriers 17 and 21 and the actuating rings 26 and 28.

The contact carriers 17 and 21, being adapted to turn, serve as actuators in direct 25 adjusting relation to the contacts carried thereby. The rings 26 and 28 serve as actuators for said contact carriers and, through these carriers, as actuators for said contacts.

Changes may be made without departing 30 from the invention.

Having thus described my invention, I claim:—

1. The combination with a casing having an opening formed through an end wall 35 thereof; of a hollow lock member fixed upon said casing end wall and in register with said opening, this lock member projecting into the interior of the casing; a pin carrier within the casing and secured to the 40 inner end of said lock member; a pin upon said pin carrier and spring pressed toward said casing end wall; a key operated lock member disposed to turn in said hollow lock member and located between said pin carrier 45 and said casing end wall; a key operated tumbler in said key operated lock member and adapted to be located in and out of register with the aforesaid pin upon turning said key operated lock member, the 50 aforesaid pin projecting into the space occupied by said tumbler when the tumbler is in register with the pin and in the absence of the key, said tumbler being key operated to position said pin and tumbler each within 55 the part carrying the same to permit the key to turn the key operated lock member; a handle mounted to turn upon the exterior of the casing, said key operated lock member being in line with the axis of the handle, 60 the handle being formed to permit passage of the key; and mechanism within the casing having one member coupled, within the casing, with the key operated lock member and another member coupled with the handle.

2. The combination with a casing having an opening formed through an end wall thereof; of a lock member fixed upon said casing end wall and in the region of said opening, this lock member projecting into 70 the interior of the casing; a pin carrier within the casing and secured to the inner end of said lock member; a pin upon said pin carrier and spring pressed toward said casing end wall; a key operated lock member disposed adjacent the first aforesaid lock member and mounted to turn and located between said pin carrier and said casing end wall; a key operated tumbler in 75 said key operated lock member and adapted to be located in and out of register with the aforesaid pin upon turning said key operated lock member, the aforesaid pin projecting into the space occupied by said tumbler when the tumbler is in register with the pin and in the absence of the key, said tumbler being key operated to position said pin and tumbler each within the part carrying the same to permit the key to turn the key operated lock member; a handle mounted to turn 80 upon the exterior of the casing, said key operated lock member being in line with the axis of the handle, the handle being formed to permit passage of the key; and mechanism within the casing having one member coupled, within the casing, with the key operated lock member and another member coupled with the handle.

3. The combination with a casing having an opening formed through an end wall 100 thereof; of a hollow lock member fixed upon said casing end wall and in register with said opening, this lock member projecting into the interior of the casing and carrying a holding part that is fixed upon its inner end; a key operated lock member disposed to turn in said hollow lock member and located between said holding part and said casing end wall; means for maintaining 105 said holding part and said key operated lock member in fixed relation and key controlled to permit the key to operate said key operated lock member; a handle mounted to turn upon the exterior of the casing, said key operated lock member being in line with the axis of the handle, the handle being formed to permit passage of the key; and mechanism within the casing having one member coupled, within the casing, with the key operated lock member and another member coupled with the handle.

4. The combination with a casing having an opening formed through an end wall thereof; of a lock member fixed upon said casing end wall and in the region of said opening, this lock member projecting into the interior of the casing and carrying a holding part that is fixed upon its inner end; a key operated lock member disposed adjacent the first aforesaid lock member and

mounted to turn and located between said holding part and said casing end wall; means for maintaining said holding part and said key operated lock member in fixed relation 5 and key controlled to permit the key to operate said key operated lock member; a handle mounted to turn upon the exterior of the casing, said key operated lock member being in line with the axis of the handle, the handle being formed to permit passage of the key; and mechanism within the casing having one member coupled, within the casing, with the key operated lock member and another member coupled with the handle.

15 5. The combination with a casing having an opening formed through an end wall thereof; of a hollow lock member fixed upon said casing end wall and in register with said opening, this lock member projecting 20 into the interior of the casing; a pin carrier within the casing and secured to the inner end of said lock member; a pin upon said pin carrier and spring pressed toward said casing end wall; a key operated lock 25 member disposed to turn in said hollow lock member and located between said pin carrier and said casing end wall; and a key operated tumbler in said key operated lock member and adapted to be located in and out 30 of register with the aforesaid pin upon turning said key operated lock member, the aforesaid pin projecting into the space occupied by said tumbler when the tumbler is in register with the pin and in the absence of the key, said tumbler being key operated to position said pin and tumbler each within the part carrying the same to permit the key to turn the key operated lock member.

6. The combination with a casing having 40 an opening formed through an end wall thereof; of a lock member fixed upon said casing end wall and in the region of said opening, this lock member projecting into the interior of the casing; a pin carrier within 45 the casing and secured to the inner end of said lock member; a pin upon said pin carrier and spring pressed toward said casing end wall; a key operated lock member

disposed adjacent the first aforesaid lock member and mounted to turn and located 50 between said pin carrier and said casing end wall; and a key operated tumbler in said key operated lock member and adapted to be located in and out of register with the aforesaid pin upon turning said key operated lock member, the aforesaid pin projecting into the space occupied by said tumbler when the tumbler is in register with the pin and in the absence of the key, said tumbler being key operated to position said pin and tumbler 60 each within the part carrying the same to permit the key to turn the key operated lock member.

7. The combination with a casing having an opening formed through an end wall 65 thereof; of a hollow lock member fixed upon said casing end wall and in register with said opening, this lock member projecting into the interior of the casing and carrying a holding part that is fixed upon its inner end; 70 a key operated lock member disposed to turn in said hollow lock member and located between said holding part and said casing end wall; and means for maintaining said holding part and said key operated lock member 75 in fixed relation and key controlled to permit the key to operate said key operated lock member.

8. The combination with a casing having an opening formed through an end wall 80 thereof; of a lock member fixed upon said casing end wall and in the region of said opening, this lock member projecting into the interior of the casing and carrying a holding part that is fixed upon its inner 85 end; a key operated lock member disposed adjacent the first aforesaid lock member and mounted to turn and located between said holding part and said casing end wall; and means for maintaining said holding part and 90 said key operated lock member in fixed relation and key controlled to permit the key to operate said key operated lock member.

In testimony whereof, I hereunto subscribe my name.

JOHN H. NELSON.
